UNITED STATES PATENT OFFICE.

FRANK H. ADAMS, OF CLEVELAND, OHIO.

REPEATING AND STOPPING ATTACHMENT FOR PHONOGRAFS.

1,317,257.

Specification of Letters Patent. Patented Sept. 30, 1919.

Application filed January 22, 1915. Serial No. 3,674.

To all whom it may concern:

Be it known that I, FRANK H. ADAMS, a citizen of the United States, residing at Cleveland, in the county of Cuyahoga and State of Ohio, have invented a certain new and useful Improvement in Repeating and Stopping Attachments for Phonographs, of which the following is a full, clear, and exact description.

10 This invention is an improvement upon the repeating and stopping attachment for phonographs which forms the subject matter of my pending application, Serial No. 859,271, filed August 31, 1914.

15 One object of this invention is to provide such repeating and stopping attachments with means by which a record may be repeated indefinitely, or any desired number of times, and which will automatically stop 20 the phonograph when the record has been played the required number of times.

Another object of the invention is to so construct such repeating and stopping attachments that a person having no particular 25 mechanical skill may be sure to apply the attachment in proper operative relation to the coöperating parts of the phonograph.

The invention consists in the construction and combination of parts shown in the 30 drawing and hereinafter described and definitely pointed out in the appended claims.

In the drawing Figure 1 is a plan view of a disk phonograph with this invention 35 applied to it; Fig. 2 is a sectional front elevation of the parts shown in Fig. 1; Fig. 3 is a bottom view of the track arm; Fig. 4 is a full size front elevation of the invention attached to a phonograph,—parts of which are 40 shown in section; Fig. 5 is a plan view of the base plate of the attachment when the track arm is disconnected therefrom; and Fig. 6 is a sectional elevation substantially in the plane of line 6—6 on Fig. 5.

45 The parts of the phonograph with which the attachment coöperates require no changes in construction. The parts of the phonograph shown in the drawing include the driving spindle 2 which projects vertically up through a horizontal partition board 1, which is a part of the phonograph cabinet; a record-supporting turntable 3 which embraces and has a driving connection with the spindle but is detachable therefrom; the tone arm 6 which is movable about a vertical axis; the U-tube 7 pivoted

to said tone arm; and the sound box 4 carried by said U-tube.

The attachment, as shown, is like that which forms the subject matter of said prior application, in that it includes a track arm 10 which is pivoted on a horizontal axis to a fixture located to one side of the turntable so that it may oscillate up and down about said pivot; and means whereby when a record has been played the free end of the track arm will be raised to cause the tone arm of the phonograph to return to the starting position and then lowered to free said tone arm from restraint and to allow the needle 5 to enter the groove of the record R. These means may include the spindle 13, detachably fixed to the spindle which rotates the turntable, and provided with the double spiral grooving; and the dog 14 movably mounted on the track arm, adapted for engagement with the grooves in said standard. As fully described in said prior application, when the needle reaches the end of the playing groove in the record, the downwardly projecting finger 14^a movable with the sound box engages a laterally projecting part 14^b of the dog and causes a spring 14^c (see Fig. 3) to shift one of the jaws of the 35 dog into the elevating groove of the spindle, causing the track arm to be elevated. As the track arm is elevated it engages a roller 14^d movable with the sound box, lifting the needle clear of the record and swinging the 40 U-tube about its axis when the sound box as a whole and the parts carried thereby move by gravity to starting position. When the dog reaches the upper end of the spindle it is rocked to its former position by a cam 14^e so as to cause the other jaw of the dog to enter into the lowering groove, whereupon the track arm is gradually lowered until it rests as before on the base of the grooved spindle. 45 But any other suitable means for raising 100 and lowering the track arm, to cause the return of the tone arm to its starting position, may be employed.

The application to a phonograph of the attachment shown and described in said prior application requires considerable mechanical skill, because said attachment has to be located in working relation to the following parts of the phonograph, viz: the tone arm, the turntable and its spindle, and the turntable brake. As before stated, one object of this invention is to render it easy

- for an ordinary person to apply the attachment to a phonograph. To effect this desirable result, two features of novelty have been introduced, viz: the spring-actuated 5 turntable brake lever 8 is mounted on the attachment, and in proper relation to the parts thereof which control its movement; and the supporting member for the track arm is made in the form of a base plate 9 having in one end a hole 9^a adapted to fit 10 loosely over the spindle 2, so that when said base plate does embrace the spindle and rests upon the horizontal partition board 1 below the turntable, the hinge for the track 15 arm will be properly located with respect to the spindle and turntable. Therefore, the person applying the attachment to the phonograph has only to exercise his judgment in so moving the outer end of the base 20 plate that the brake will properly engage the turntable; and having properly located the attachment with this purpose in view, the attachment may now be permanently fastened to the partition board 1.
- 25 The outer end of the base plate 9 is turned up to form the flange 12, and it is to the upper edge of this flange that the track arm is hinged.
- The brake lever 8 is, as stated, pivoted to 30 the base plate. This is accomplished by means of a curved pivot stud 15 which may be formed integrally with the upturned rear flange 16 of the base plate 9. This stud goes rather loosely through a hole 8^a in the 35 brake lever, and, therefore, said lever may not only swing in a horizontal plane toward and from the turntable, but the free end of it may also be moved up and down sufficiently to enable it to coöperate with the restraining devices to be presently explained.
- 40 This brake lever is under the influence of a spring 17 tending to move it toward the turntable, and it is provided with an arm 8^b, adapted to engage the edge of the turntable, 45 and apply braking pressure thereto.
- Associated with this brake lever is an escapement device which is adapted to be operated by the to and fro, *i. e.*, the up and down movements of the oscillating track 50 arm, by which this brake lever is held away from the turntable, but is released and allowed to come into braking engagement therewith after the record has been played 55 any desired number of times, within the capacity of the device.
- In the construction shown, provision is 60 made by which the record may be played one, two or three times, as desired, and then the phonograph automatically stopped.
- 65 In the particular construction of this escapement mechanism which is embodied in the device shown in the drawing, a flange 19 is turned up along the front edge of the base plate 9, and in this flange is a hole 19^a through which the free end of the brake
- lever extends. That edge of this hole which is nearest the turntable is formed with a plurality of stepped shoulders *a*, *b*, *c*, and below them a notch 20^a, and below that a shoulder 22. When the brake lever engages shoulder 22 it will be held out of braking engagement with the turntable until it is manually disengaged from this shoulder. When, however, the brake lever is in line with the notch 20^a, that lever, actuated by its spring, 70 may move into braking engagement with the turntable and thereby stop its rotation. If the brake lever is in engagement with either of the shoulders *a*, *b*, and *c*, it is likewise held out of engagement with the turntable. 75
- On the under side of the track arm 10 is a depending bracket 20 which lies close to and behind the flange 19. On that edge of this bracket which is farthest from the turntable are a plurality of stepped shoulders 85 *d*, *e*, *f*, placed substantially as shown with respect to the shoulders *a*, *b*, *c*, so that the shoulders on the bracket and the shoulders on the flange will coöperate in pairs. That is to say, the shoulder *d*, for example, is at 90 a slightly greater distance from the turntable than is the associated shoulder *a*, and is in a slightly lower plane when the track arm is down; and is also below a horizontal surface *a'* leading off from the upper shoulder *a*. The shoulder *e* occupies a corresponding relation to the associated shoulder *b*, and the off-leading horizontal surface *b'*; and the shoulder *f* occupies a corresponding position relative to the shoulder *c* and its 95 off-leading surface *c'*.
- Likewise, the shoulders *a*, *b*, *c*, and *d*, *e*, *f*, are slightly undercut, and the corresponding edge of the brake lever is also undercut as at 8^a—this undercutting being for the 100 purpose of insuring that the parts shall operate in the manner now to be described.
- In starting the phonograph, the track arm will be in its horizontal position shown in Fig. 2. In case it is desired that the record shall be played three times, the brake lever will be drawn back and moved up into engagement with the shoulder *d*, as shown in Fig. 4. When the record has been played once the track arm will be raised as by the 110 mechanism shown in the prior application, or other suitable mechanism. As it goes up, the brake lever will be carried up into contact with the associated overlying surface *a'*, by which it will be pushed out of engagement with the shoulder *d*, and will be allowed to move into engagement with the shoulder *a*. Then, when the track bar descends, the bracket 20 will engage the lever 115 and push it down out of contact with shoulder *a*, and allow it to fly into engagement with the shoulder *e*. These operations will be repeated with each to and fro movement of the track arm, the brake lever passing 120 progressively from shoulder *e* to shoulder *b* 130

and then to shoulder *f* on the next to and fro movement of the brake arm, and then from shoulder *f* to shoulder *c*, and thence into notch 20^a on the third to and fro movement of said track arm.

As before stated, when the brake lever enters notch 20^a it will apply braking pressure to the turntable and stop it,—the record in the meantime having been played three 10 times. If it is desired to play the record only twice the brake lever would be initially placed in contact with shoulder *e*. If once only, it should be placed in contact with shoulder *f*.

15 It is to be understood that if one wishes to play the record indefinitely he will place the brake lever in engagement with the shoulder 22.

The word "phonograph" as used in the 20 specification and claims, is not intended to limit this application to a machine sold under the trade-name "Phonograph" but includes any sound reproducing or so-called talking machine utilizing a disk record, or 25 of the general type herein shown and described.

Having described my invention, I claim:—

1. In combination with a phonograph having a turntable and a tone arm, of a repeating and stopping attachment comprising 30 a spring actuated brake, and means including a vertically swinging arm for returning the tone arm to starting position a predetermined number of times and for then 35 permitting the brake to be actuated to stop the turntable.

2. A repeating attachment for phonographs of the type having a spindle driven turntable and a tone arm, said attachment 40 comprising two arms, one pivoted relative to the other, and both adapted to extend from beyond the periphery of the turntable inwardly toward the center thereof, one of said arms having an opening for the spindle 45 and the other adapted to be swung relative to the first to restore the tone arm to starting position.

3. A repeating attachment for phonographs of the disk record type having a 50 spindle driven turntable, said attachment comprising two arms, both adapted to extend inwardly from beyond the turntable toward the center thereof, one of said arms having an opening for the turntable spindle, 55 and the other movable relative thereto to cause the tone arm to be restored to starting position, together with means for shifting said second arm.

4. A repeating and stopping attachment 60 for phonographs of the disk record type having a spindle driven turntable, said attachment comprising a unit including two arms adapted to extend inwardly from beyond the periphery of the turntable toward the 65 center thereof, one of the arms having an

opening for the turntable spindle and the second arm pivoted to swing relative to the first, and said unit comprising also a brake adapted to engage the turntable and controlled by the movement of said second arm. 70

5. A repeating and stopping attachment for phonographs of the disk record type having a spindle driven turntable, said attachment comprising a unit including two arms adapted to extend inwardly from beyond the periphery of the turntable toward the center thereof, one of the arms having an opening for the turntable spindle and the second arm pivoted to swing relative to the first, and said unit comprising also a 75 brake adapted to engage the turntable and controlled by the movement of said second arm, and said attachment including in addition to said arm and means adapted to be rotated by the turntable spindle to elevate 80 the second arm.

6. In combination with a phonograph having a platform, a turntable above the platform, a spindle for driving the turntable, a tone arm and sound box, a repeating mechanism including a track arm pivoted beyond one side of the turntable and adapted to extend inwardly over the same, means for raising the inner end of the track arm, and a support for the outer 90 end of the track arm comprising a member mounted on the platform and extending under the turntable to said spindle.

7. In combination with a phonograph having a horizontal platform, a turntable, 100 a vertical spindle for turning the turntable, a sound box and tone arm, a repeating mechanism comprising a track arm pivoted at one side of the turntable and adapted to extend inwardly over the same, means for 105 elevating the inner end of the track arm, and a support for the outer end of the track arm comprising a member to which the track arm is pivoted, said member having an arm extending along the platform beneath the turntable and having at its inner end an opening through which said spindle 110 extends.

8. A repeating mechanism for phonographs having a driving spindle and a turntable for rotating disk records, said mechanism comprising a supporting device adapted to be positioned beyond the turntable and provided with a director arm adapted to extend inwardly to the spindle 115 and having an opening for the latter and provided also with a track arm pivoted at its outer end and adapted to extend inwardly toward the spindle together with means adapted to be rotated by the spindle 120 for elevating the inner end of the track arm.

9. A repeating mechanism for phonographs having a turntable, a driving spindle, a tone arm and a sound box, said 130

mechanism comprising a grooved elevating device adapted to be rotated by the spindle and a member adapted to be positioned beyond the turntable and having two arms 5 adapted to extend inwardly from beyond the turntable toward the spindle, one of said arms having at its inner end an opening adapted to be positioned coaxially with the spindle and the other arm which is above 10 the first-named being pivoted at its outer end and having at its inner end a member adapted to engage the grooved elevating device.

10. The combination in a repeating and 15 stopping mechanism for sound reproducing machines of the disk record type having a turntable, a tone arm and a reproducer, of means for lifting the reproducer and causing the tone arm to swing toward the periphery of the turntable, a brake and a 20 spring acting thereon to shift the same to braking position against the turntable, means for holding the brake retracted, and mechanically operated means controlled by 25 the lifting means for releasing the brake from the retracting means so that it may be actuated by the spring to perform its braking function after either one or a plurality of actuations of the lifting means, the 30 releasing means comprising an escapement having a plurality of serrations.

11. The combination in a repeating and 35 stopping mechanism for sound reproducing machines of the disk record type having a turntable, a tone arm and a reproducer, of means for lifting the reproducer and causing the tone arm to swing toward the periphery of the turntable, a brake and a 40 spring acting thereon to shift the same to braking position against the turntable, means for holding the brake retracted, and mechanically operated means controlled by 45 the lifting means for releasing the brake from the retracting means so that it may be actuated by the spring to perform its braking function after either one or a plurality of actuations of the lifting means, the 50 means for holding the brake retracted comprising a series of teeth or steps from which the brake is released consecutively by operations of the lifting means.

12. The combination with a phonograph 55 repeating mechanism having a movable member, a pivoted brake lever for engaging the periphery of the phonograph turntable, restraining means preventing the brake from acting, and escapement mechanism operated by the to and fro movements of said movable part of the repeating mechanism for causing 60 said brake lever to move step by step toward and finally into contact with said turntable.

13. The combination with a phonograph 65 repeating mechanism having a movable member, of a spring actuated brake for stop-

ping the phonograph, a series of brake restraining steps, with either of which the brake may engage, and mechanism actuated by said moving part of the repeating mechanism for moving said brake progressively 70 from one restraining step to another, and finally off of the terminal restraining step of the series.

14. The combination with a repeating mechanism for phonographs which includes 75 a track arm and means for causing it to oscillate up and down periodically, of a spring actuated brake lever, a fixed flange having on one edge a series of brake restraining steps—with any one of which the brake lever 80 may engage,—and a bracket fixed to said track arm and having on one edge a series of coöperating brake restraining steps,—with any one of which the brake lever may engage,—said steps being arranged substantially as shown, whereby the up movement of said track arm will cause the lever to be pushed out of engagement with a step carried thereby, and whereby the down movement of said track arm will cause said lever 90 to be pushed out of engagement with one of the fixed brake restraining steps.

15. A repeating and stopping attachment 95 for phonographs, which includes a base plate having a hole in its end through which the phonograph spindle may pass, and having at its other end an upturned flange, a track arm pivoted to the upper edge of said flange and adapted to extend therefrom over the turntable of the phonograph, means for 100 periodically causing the free end of said track arm to move up and down, and a brake lever pivoted to said base plate,—said base plate being also provided with shoulders with which said brake lever may engage and 105 be thereby restrained from operating.

16. A repeating and stopping attachment 110 for phonographs, comprising a track arm pivoted on a horizontal pivot and adapted to extend therefrom over the turntable of the phonograph, means for periodically causing the free end of said track arm to move up and down, a fixed vertical flange having a hole through it, a spring actuated brake lever which, mounted on a pivot, permits a limited universal movement, and is extended through said hole, said hole being provided at one edge with a notch in which the brake lever may travel and thereby move into operative position, and adjacent said notch a shoulder with which the brake lever may be caused to engage and be thereby held against movement to the operative position.

17. In combination with a phonograph 115 having a turntable and a pivoted tone arm, a repeating and stopping attachment, which includes a brake lever, a track arm pivoted on a horizontal pivot and adapted to extend 120 therefrom over the turntable of the phono-

graph, means for periodically causing the free end of said track arm to move up and down, with a vertical flange having a hole through it, said hole being provided at one edge with a notch in which the brake lever may travel and thereby move into operative position, and above said notch with a plurality of brake restraining steps, with any one of which said brake lever may be caused to engage, and means whereby the track arm will progressively move said lever from one step to another, and finally off of the terminal step, and allow it to enter said notch.

18. The combination with a phonograph having a turntable, of an arm pivoted on a horizontal axis to one side of the turntable of the phonograph, mechanism operated by the phonograph for causing said arm to swing up and down, a spring actuated brake for stopping the phonograph, means restraining the brake from acting, and escapement mechanism operated by the to and fro movements of said pivoted arm for causing the brake to move step by step toward and finally into contact with said turntable.

19. A repeating and stopping attachment for phonographs comprising a member adapted to be secured to the phonograph at one side of the turntable thereof, a track

arm pivoted to said member and adapted to extend over the turntable, a brake lever, said member having a series of brake restraining shoulders and a brake releasing notch, and means for causing the track arm to be raised and lowered and for causing the brake lever to be moved from shoulder to shoulder and then into said notch.

20. A repeating and stopping attachment for phonographs comprising a member adapted to be secured to the phonograph at one side of the turntable thereof, a track arm pivoted to said member and adapted to extend over the turntable, a brake lever, said member having a series of brake restraining shoulders and a brake releasing notch, means for causing the track arm to be raised and lowered and for causing the brake lever to be moved from shoulder to shoulder and then into said notch, and said member having adjacent the notch a shoulder against which the lever is adapted to be placed to permit continuous repeating.

In testimony whereof, I hereunto affix my signature in the presence of two witnesses.

FRANK H. ADAMS.
